Primary Examiner — Lucy Lieberman*(74) Attorney, Agent, or Firm* — Sughrue Moin, PLLC**CLAIM**

The ornamental design for a watch case, as shown and described.

DESCRIPTION

FIG. 1 is a right-top perspective view of the watch case;

FIG. 2 is a top view of the watch case;

FIG. 3 is a right side view of the watch case; and,

FIG. 4 is a left side view of the watch case.

The broken lines depict environment only and form no part of the claimed design.
